SLOW STARTING HIGH SPEED WIRE
DRAWING BLOCK

Frank G. Mog, Cleveland, George F. Wald, North
Olmsted, and Samuel C. Whiting, Willoughby,
Ohio, assignors to The American Steel and Wire
Company of New Jersey, a corporation of New
Jersey

Application November 24, 1942, Serial No. 466,776

7 Claims. (Cl. 205—16)

In wire or rod drawing operations, the work being drawn customarily is pulled through the drawing dies by means of a rotary power-driven drawing block upon which the drawn wire or rod is wound as it is pulled through the dies, the output from the dies being determined and limited by a number of factors, one of which is the speed at which the work is drawn through the dies, which speed is determined by the acceleration of the drawing block from zero to maximum speed thereof. If this acceleration is too high, the wire will break before the block reaches its maximum speed.

In accordance with the present invention there are provided certain improvements in the construction of the drawing block, whereby the output of the drawing operation is very substantially increased, and the block can be operated at a much higher speed than formerly but without danger of breaking the wire during acceleration of the block to the higher speed.

In general, it may be noted that for simplicity and economical maintenance, a jaw clutch is used in the conventional practice to start the block. But a jaw clutch starts a block almost instantly, so that therefore the maximum speed that wire can be drawn in this manner is comparatively low. Accordingly, in accordance with the present invention, to obtain a higher speed, mechanism has been developed whereby the block is brought to full speed by two successive steps as will become apparent hereinafter.

The invention will be understood more readily by the referring to the accompanying drawings, wherein:

Fig. 1 represents a sectional elevation of the improved apparatus;

Fig. 2 is a sectional elevational side view of the apparatus of Fig. 1, taken along the line II—II looking in the direction of the arrows;

Fig. 3 is a part front elevation of the apparatus of Fig. 1, showing in more detail the positions taken by the clutch operating levers during the operation of the machine.

Referring more particularly to the drawings, the reference character A represents a frame on which is mounted a block B for pulling wire C through drawing dies, a die-housing being indicated at D.

Customarily, the drawing block B operates at a single speed, the acceleration to this speed being sufficiently slow to avoid breaking the wire being drawn.

A drive shaft 5 is shown as carrying a beveled gear 7, the shaft 5 being driven from a suitable

source of power (not shown). The gear 7 in turn meshes with a beveled gear 9 which is mounted on a spindle 11 and is freely rotatable around the said spindle, so that the gear 9 is rotating continuously and independently of the spindle.

The gear 9 has a spur gear 13 mounted on it, the spur gear 13 being shown as an integral part of the beveled gear 9. Spur gear 13 meshes with a spur gear 15 mounted on a countershaft 17 and keyed to the shaft so that the gear 15 and shaft 17 are rotating continuously with the gears 7 and 13.

Gear 13 carries a spiral clutch member 19, while spindle 11 has keyed to it for vertical movement as well as rotation with the spindle, the complementary spiral clutch member 21 which is controlled by lever 24 and yoke 25. Spindle 11 carries the block B and drives this block at the conventional speed of shaft 5 and gears 9 and 13 responsively to actuation of the clutch member 21 to engage it with clutch member 19, thereby driving the spindle 11 at the said conventional speed.

Spindle 11 also has a gear 23 keyed to it, this gear meshing with a gear 25 freely rotatable relative to the countershaft 17. Gear 25 has spiral clutch member 27 mounted on it, while a complementary spiral clutch member 29 is keyed to countershaft 17 for vertical movement thereon responsive to actuation of lever 31 and connecting yoke 33. It will be seen that gear 15 is substantially smaller than gear 13, it being in practice about half the size of gear 13 with half the number of gear teeth as has the gear 13. Therefore, the gear 15 and countershaft 17 are driven at twice the number of revolutions of the gear 13 and also twice the number of revolutions of spindle 11 responsively to engagement of the clutch members 19 and 21.

With the spindle 11 rotating, gear 23 will rotate at the same speed as the spindle, as does also the gear 25, which, however, freely rotates relative to the countershaft.

Now, when lever 31 is actuated it brings clutch members 27 and 29 into engagement, and clutch member 29 will drive the gear 25 not at its former speed, but at the speed at which the countershaft 17 is rotating, which is twice the former number of revolutions of gear 25, that being the same as spindle 11.

Gear 23 is, in practice, about half the size of gear 25 and carries half the number of teeth, gears 13 and 25 being duplicates and gears 23 and 15 being duplicates. Therefore, since gear

13 drives gear 15 and countershaft 17 at twice the number of revolutions as gear 13 is turning, and since this doubled speed is again doubled on gear 23 upon engagement of clutch member 29 with clutch member 27, engagement of such clutch members actually causes the spindle 11 to be rotated at four times the number of revolutions at which the gear 13 is rotating, thereby accelerating accordingly the speed of the block B.

When the spindle 11 rotates thus faster, clutch member 21, which is keyed to the spindle 11, rotates faster than clutch member 19 so that clutch member 21 disengages from clutch member 19 until the members completely separate.

As the clutch member 21 moves to this position, its control lever 24 moves in slot 32 in the housing from a lowermost position 33^a to an intermediate position 33^b from which position spring 35, which is secured to lever 24, pulls the lever into position 33^a at which position the clutch member 21 becomes totally disengaged from clutch member 19.

This motion of the lever 24 from position 33^b to position 33^a is accomplished because of the curvature of the slot 32, as is indicated at 31, this portion 31 of slot 32 having an arcuate curvature for guiding the lever in its movement.

With clutch 21 completely disengaged from its counterpart 19, the block B is free to rotate at the accelerated speed. To stop the movement of the block, lever 31 is moved from position 33^b to position 33^a, this lever operating in a slot 39 the upper end of which is off-set to form a shoulder 41 for holding the lever.

Levers 24 and 31 are operated manually. To initiate the operation of the block B, lever 24 is moved from top position 33^a in slot 32 to lowermost position 33^c, thereby engaging clutch members 21 and 19. Disengagement of this clutch during accelerated rotation of the block B causes a corresponding lifting of the lever 24 from the lowermost position 33^c to intermediate position 33^b from which intermediate position spring 35 pulls the lever over into its top position 33^a.

That is to say, lever 31 is moved to engage clutch members 27 and 29, thereby accelerating rotation of the spindle 11. Responsively to this acceleration, clutch member 21 overruns clutch member 19, so that these members separate automatically. This automatic separation moves lever 24 from its lowermost (clutch-engaging) position 33^c to the intermediate position 33^b, from which intermediate position, the spring 35 pulls the lever into the top position 33^a, with attendant further separation of the clutch members 21 and 19.

When a few turns of wire have been wound on the block B, the clutch members 27 and 29, are engaged by moving lever 31 from its topmost position 33^a in slot 39 to lowermost position 33^b at the bottom of the slot 39. To stop the block B, lever 31 is lifted from the position 33^b to position 33^a, thereby disengaging clutch member 29 from its counterpart 27 and breaking the driving connections to its spindle.

We claim:

1. Dual speed power-transmitting mechanism for rotating a wire drawing block, which comprises, in combination with the wire-drawing block, of a driving shaft, driven shaft, a driving bevel gear mounted upon the driving shaft for rotation therewith, a second bevel gear on the driven shaft and rotatable independently thereof, the second gear meshing with the gear on the driving

shaft and operated thereby, the said driven shaft carrying the wire-drawing block, a spur gear forming a part of the said second bevel gear, and including a spirally fast clutch member continuously rotatable with the said gear, complementary clutch members on the driven shaft and slidably mounted relatively thereto, means for contacting the said clutch members to rotate the driven shaft and block at a speed corresponding to gear ratios 10 between the bevel gear on the driving shaft and the said second bevel gear, a countershaft, a second spur gear mounted on the countershaft in engagement with the said spur gear on the second bevel gear, and having a ratio relative thereto for driving the countershaft at a predetermined rate 15 faster than the speed of rotation of the said driven shaft, a third spur gear mounted on the countershaft rotatable relative thereto and including a clutch member rotatable with the said gear, a fourth spur gear mounted on the driven shaft 20 and having a ratio with reference to the third spur gear such that the driven shaft will be accelerated in rate a predetermined amount responsively to actuation of the gears, thereby accelerating speed of rotation of the block, a clutch member slidably mounted on the countershaft, and means for engaging the said clutch member with the clutch member on the said third spur gear, engagement of the countershaft clutch members causing an automatic disengagement of 25 the driven shaft clutch members, thereby permitting acceleration of the speed of the driven shaft and block while the second bevel gear is rotated continuously at the speed imparted thereto by the gear on the driving shaft.

2. Multiple speed mechanism for driving a wire-drawing block at a plurality of speeds, which comprises the combination with the wire-drawing block, of a driving shaft, relatively slow starting speed mechanism continuously driven by the driving shaft, a second shaft for rotating the block adapted to be driven directly by the starting speed mechanism, means for selectively engaging and disengaging the second shaft relative to the starting speed mechanism, second speed mechanism continuously driven by the starting speed mechanism, driving instrumentalities between the second speed mechanism and the said second shaft adapted to rotate the said shaft at a speed 40 greater than that of the second speed mechanism, and means for selectively operating the driving mechanism, the direct driving means for the second shaft being adapted to disengage the said shaft from the first speed mechanism responsively to acceleration of the speed of the second shaft incident to operation of the said driving instrumentalities.

3. Multiple speed mechanism for driving a wire-drawing block at a plurality of speeds, comprising the combination with the wire-drawing block, of a continuously driven power-transmitting shaft, relatively slow starting speed mechanism operated by the driving shaft, relatively fast second speed mechanism driven by the starting speed mechanism, a shaft for rotatably mounting the block, selectively operable mechanism for driving the said second shaft from the second speed mechanism at a speed faster than the said second speed mechanism, and means for automatically rendering the first speed mechanism inoperative on the said second shaft responsively to actuation of the selectively operable driving mechanism.

4. Multiple speed mechanism for driving a wire-drawing block at a plurality of speeds comprising,

in combination with the wire-drawing block, of a power-transmitting shaft, a driving gear on a said shaft, a relatively slow starting speed gear constantly driven by the said driving gear, a second shaft for rotatably mounting the block, clutch mechanism adapted to engage the said starting speed gear for directly driving the second shaft and block from said gear, a countershaft continuously driven by the starting speed gear, means rotating the said countershaft at a speed greater than that of the starting speed gear, a selectively operable driving mechanism connecting the countershaft with the second shaft and adapted upon actuation of the said mechanism to drive the second shaft at a speed substantially greater than that of the countershaft, and clutch mechanism for operating the said driving mechanism at the said greater speed, the said second shaft being automatically disengaged from the first starting speed gear responsively to operation of the driving means.

5. Multiple speed mechanism for driving a wire-drawing block at a plurality of speeds, comprising the combination with the wire-drawing block, of a driving shaft, relatively slow starting speed gear continuously driven by the shaft, a second shaft rotatably carrying the block, spiral-surfaced complementary clutch members for selectively engaging and disengaging the second shaft with the starting speed gear, a countershaft, means for continuously driving the countershaft from the starting speed gear at a speed substantially greater than that of the starting speed gear, driving mechanism for driving the second shaft from the countershaft at a greater speed of rotation than that of the countershaft, and second clutch mechanism for operating the said driving mechanism, the actuation of the second clutch with a resultant acceleration of the second shaft causing separation of the spirally-surfaced complementary clutch members to drive the second shaft at a speed substantially greater than that of the starting speed gear.

6. Multiple speed mechanism for driving a wire-drawing block at a plurality of speeds, which comprises the combination with the wire-drawing block, of a driving shaft, relatively slow starting speed gear constantly driven by the said driving shaft, the said starting speed gear defining a spirally-surfaced clutch member, a second shaft, a complementary spirally-surfaced clutch member slidably mounted on the said shaft, the said

second shaft carrying the block, a countershaft, means for continuously driving the countershaft from the starting speed gear at a speed substantially in excess of the said gear, power transmitting mechanism from the countershaft to the second shaft adapted, when actuated, to drive the second shaft at a speed greater than that of the countershaft, a clutch for operably connecting the said power-transmitting mechanism to the countershaft for driving the second shaft at a speed substantially greater than that of the countershaft, the slidably mounted clutch member on the second shaft being adapted to separate automatically from the clutch member on the first starting speed gear, thereby enabling the second shaft to be driven at a speed greater than the starting gear, which starting gear continues to operate the countershaft.

7. Multiple speed mechanism for driving a wire-drawing block at a plurality of speeds, comprising the combination with the wire-drawing block, of a power-transmitted shaft, relatively slow starting speed mechanism continuously operated by the driving shaft, a relatively fast second speed mechanism including a countershaft continuously driven by the starting speed mechanism, a second shaft for rotatably mounting the block, selectively operable mechanism for driving the said second shaft from the second speed mechanism at a speed faster than the second speed mechanism, and means for automatically rendering the first speed mechanism inoperative on the second speed shaft responsively to actuation of the selectively operable driving mechanism, whereby the said block is driven at a greater speed than the countershaft while the starting speed mechanism continues to drive the countershaft, the second speed mechanism being driven by the starting speed mechanism by a train of gears having a ratio such that the countershaft is driven at approximately twice the speed as the starting speed mechanism, and the selectively operable mechanism for driving the second shaft including a train of gears having a ratio such that the second shaft is driven at substantially twice the speed of the countershaft, or substantially four times the speed of the starting speed mechanism, responsively to actuation of the said selectively operable driving mechanism.
